UNITED STATES PATENT OFFICE.

OSCAR A. BIGLER, OF WYOMING, OHIO, ASSIGNOR TO THE PHILIP CAREY MANUFACTURING COMPANY, OF CINCINNATI, OHIO, A CORPORATION OF OHIO.

ROOFING.

1,284,997.

Specification of Letters Patent. Patented Nov. 19, 1918.

Application filed July 6, 1918. Serial No. 243,608.

To all whom it may concern:

Be it known that I, OSCAR A. BIGLER, a citizen of the United States, and a resident of Cincinnati, in the county of Hamilton and State of Ohio, have invented certain new and useful Improvements in Roofing, of which the following is a specification.

My invention relates to roof construction and fabrics used therein, and its object is to facilitate the construction of a roof with the use of fabric laid in successive layers or plies with the successive widths of fabric overlapping; and especially in such construction where the fabric has combined with it a suitable impregnating and coating substance, in which case, my invention has for one of its objects the assurance of greater continuity of the impregnating and coating body throughout the structure. Other objects will more fully appear in the ensuing description.

My invention consists in the improved roof construction and in the details of said construction and the arrangement of its parts and in the improved roofing fabric as a new article of manufacture, all of which will be more fully described and claimed herein.

In the drawing:

Fig. 1 is a perspective view of the upper part of a small building with its roof in a partial stage of completion according to my invention;

Fig. 2 is a vertical cross-section of part of the roof shown in Fig. 1 in its completed condition;

Fig. 3 is a partial cross section much enlarged;

Fig. 4 is a perspective view of a roll of fabric partly unrolled; and

Fig. 5 is a smaller perspective view of a roll of the fabric in rolled-up and closed condition ready for storage, transportation and sale.

The type of roof construction in which my invention is involved is well known and will be readily recognized upon inspection of Figs. 1, 2 and 3. Upon the sheathing 1 of the slanting roof along the lowest edge or eave 2 thereof is laid a narrow strip 3 of fabric. Over this and also along this edge 2 is laid a second strip 4 of fabric twice as wide as the first strip 3; the upper half of which thus laps out upon the sheathing 1. Upon this is laid a third strip

5 three times as wide as the first strip 3; so that the upper one-third of this strip 5 thus laps out upon the sheathing 1. Then a fourth strip 6 four times as wide as the first strip 3 is laid over the strip 5; so that the upper one-fourth of its width laps out upon the sheathing 1. In practice, the fabric is supplied in one width only, i. e., that of the strip 6; and the narrowest strip 3 is obtained by cutting a full width of the fabric throughout its length one-fourth of the way across from one edge; so that the other three-fourths of the width thus left makes the strip 5. Two strips 4 are made by cutting the full width of fabric along its middle throughout its length. These strips of varying widths thus cut and laid, as described, make the roof ready for the successive full widths 7 like the strip 6; the first being laid to lap down over three-fourths of the width of the strip 6 entirely along the roof, and the next one lapping over three-fourths of the width of this strip 7, and so on, until the other side or comb of the roof is approached. Then when so much of this fabric has been laid that the last width laid brings its edge close to the comb or other edge of the roof, a three-quarter width strip 8 is laid; then a half strip 9 and finally a quarter strip 10.

This process of laying the fabric is readily described and understood. But, in practice, except with the most skilled and careful workmen, there is considerable waste in cutting the strips of various widths required at beginning and finishing of a given roof area, as well as due to the inaccuracy of the lapping. The object of laying the roof in this way is to have it, when completed, of exactly four-ply thickness throughout, i. e., so that there will be no part of its area which, if cut squarely through would show more than four thicknesses of the fabric; and at the same time have the succeeding strips of fabric overlapped to the maximum degree permitted by this overlapped four-ply method of laying. In short, the requirement is that the exposed edge of each overlapped strip should exactly coincide with the overlapped edge of the fourth preceding strip, so that between these two edges there will be three thicknesses of fabric and extending in both directions from the plane in which these two edges coincide there will be four thick- 110

nesses of fabric. If these edges do not thus coincide, and the inaccuracy is in the direction of lapping one over the other, then there is this much of the roof with five thicknesses of fabric, and therefore a use of more material than the plans or specifications call for, and presumably that much wasted material. On the other hand, if the inaccuracy is in the other direction, there is this much of the roof with only three thicknesses of material, so that the roof is inferior in this respect and does not comply with the plans or specifications. Moreover, any workman laying such a roof with any approach to such accuracy as is required, will spend considerable time in trying and trimming and adjusting the various layers, so that the expense of laying the roof is considerable, if such waste of material or inferiority of the completed roof is to be avoided.

When all of the fabric has been laid, which is preferably a felt impregnated with a suitable substance, preferably bituminous substance or tar, the entire exposed surface is given a coating of such substance. In fact, in general practice, the wooden sheathing 1 is covered with sheet material 1', which is coated with the substance and the surface of each strip is coated with the substance before the next succeeding strip is laid thereon. The result is that the completed fabric structure has under it and all through the interstices between its layers and all over it a more or less continuous body of this impregnating or coating substance as is shown in Fig. 3, where the transverse heavy lines indicate the interstitial substance. The object, of course, is to render the roof moisture-resisting in as high a degree as possible, and also to bind together the various pieces of fabric thus laid. It will be understood that the fabric is fastened down by any suitable well-known means, generally with nails.

In order to overcome the difficulties just pointed out, as well as to increase the continuity of the impregnation and coating, I provide a roofing fabric of tarred felt or any other desired roofing material in sheet form which is preferably, although not necessarily, flexible, with a plurality of perforations so arranged as to act as indices for the cutting and lapping of the successive strips of fabric, and which, when the structure is completed, will be filled with the impregnating or coating substance and permit the bodies of substance in these perforations to thus bind together the layers of the substance on the opposite sides of the perforated sheet.

Such a sheet or strip 11 is clearly shown in Fig. 4. The perforations 12 are preferably triangular and are arranged throughout the length of the sheet 11 in three different alignments, 13 at the middle and 14 and 15 half way from the middle to respec-

tive longitudinal edges of the sheet 11. Preferably, the triangular openings 12 are all so positioned that one side of the triangle lies along the line in which the perforations of the particular series are arranged, as just described; and preferably the triangles all point toward one edge of the sheet which will be the edge placed uppermost on the roof. The object of this particular arrangement of the perforations 12 relative to their triangular shapes and, indeed, of making them triangular, is their better functioning as indices. It will be understood, however, that the particular shape of the perforations or relative positions with respect to any particular shape, is not essential to the broad conception of my invention.

These perforations 12 are spaced about twice as far apart in their respective series as the series is spaced from the edge of the sheet or from an adjacent series: and, preferably, those of the middle series 13 come half way between those of the outer series 14 and 15 with respect to longitudinal spaces. That is to say, the perforations are "staggered." This particular arrangement also is merely preferable and not essential.

With these perforations thus provided in three series defining four longitudinal divisions of the strip or sheet 11, the workman may very readily cut off one-fourth of the strip throughout its length by following either the series 14 or the series 15, or he may cut the strip into two equal parts throughout its length by following the series 13. If the perforations 12 are triangular and have their straight sides along the lines which they indicate, the indication is a little more clear than if these perforations are round or of other shape, or if they are triangular and with their points along the line of cutting. Also, when the sheet is cut along these straight edges of the triangular perforations 12, the edge of the strip left with the perforations is of better shape since it will have wide open notches rather than imperfectly closed ones which would result from cutting into the points of the triangles.

The same guidance is afforded by these various series of perforations 12 when the edge of one sheet is to be lapped over a preceding sheet, according to the well-known method hereinbefore described. The workman may very readily unroll the material, so that its edge coincides with the straight sides of the triangular openings 12 in the series 15. The overlapping sheet thus covers these perforations in this series and also the perforations in the other two series 13 and 14.

The preceding sheet having been coated with the impregnating or coating material 16 (Fig. 3) bodies 17 of this material will have filled all of the perforations 12 in all of the series 13, 14 and 15 of this preceding

sheet, and it will be seen that when this next sheet is overlapped it will be directly connected by these bodies 17 to the second preceding sheet, as will be readily understood upon inspection of Fig. 3.

Thus, all of the perforations in all of the series are useful in cutting one-quarter, one-half and three-quarter strips as required in starting and finishing the laying; and the 10 lowermost series 15 is useful in guiding the overlapping throughout the laying; and all of the perforations perform an additional function of permitting this continuous structure of impregnating or coating material 16, 15 not only throughout the flat surfaces of the layers, but in all of the bodies 17 extending through the perforations. The laminated roof structure is thus firmly bound together by the moisture-resisting and elastic substance 16 in a much better way than where this substance is merely distributed between the flat surfaces of the sheets as heretofore employed.

It will be noted that no perforations are 25 exposed on the completed structure; since every layer up to the last one 10 is made to overlap all of the exposed perforations in the preceding layer. The only irregularities in the completed structure are the exposed 30 overlapping edges which have a stepped formation like shingles. This surface is finally coated with the substance 16, as hereinbefore alluded to.

Another advantage of the use of the perforations is in the appearance given to the fabric when it is completely rolled up and ready for storage, shipment or sale. These perforations, especially if they are of peculiar shape, serve as very conspicuous identification marks for the fabric, thus supplementing the function of the label 18, as seen in Fig. 5.

While certain constructional details are deemed preferable in connection with my invention, and I have shown and described these rather specifically in elucidating the construction and use of my invention, as is required, I do not wish to be understood as being limited to such precise showing and description, but having thus fully described my invention, what I claim as new and desire to secure by Letters Patent is:

1. A roofing element having a plurality of longitudinally arranged holes means spaced at equal distances from each other transversely of the element, and said means adjacent to the longitudinal edges of said element being spaced as far from the respective edges as said means are spaced from each other, as aforesaid.

2. A roofing element having a plurality of longitudinal series of indicia, said series being spaced equally distant from each other transversely of the element, and the series different to the longitudinal edges of the

element being spaced from the respective edges as far as said series are spaced from each other, as aforesaid.

3. A roofing element having a plurality of longitudinal series of perforations, said series being spaced equally distant from each other transversely of the element, and the series adjacent to the longitudinal edges of the element being spaced from the respective edges as far as said series are spaced from each other, as aforesaid.

4. A roofing element having a plurality of series of longitudinally aligned triangular perforations with sides lying in the longitudinal alignment of the respective series, and spaced at required intervals across said element.

5. A roofing element having a plurality of series of longitudinally aligned triangular perforations with sides lying in the longitudinal alignment of the respective series, said series being spaced equal distances from each other transversely of said element, and the series adjacent to the longitudinal edges of the element being spaced from the respective edges the same distance that said series are spaced from each other, as aforesaid.

6. A laminated roof construction in which an intermediate lamina is perforated, and a substance between the laminae and extending through the perforation of said intermediate lamina, for the purpose as set forth.

7. A laminated roof construction in which the laminae are fibrous, and in which an intermediate one of said fibrous laminae is perforated, and a coating substance permeating the interstices between said laminae and extending through the perforation of said intermediate lamina, for a purpose as set forth.

8. A laminated roof construction in which succeeding laminae only partly overlap preceding laminae, and the preceding laminae having perforations under the overlapping laminae, and a substance permeating the interstices between the overlapping parts of the laminae and extending through said perforations, for a purpose as set forth.

9. A laminated roof construction in which the laminae are fibrous, and in which succeeding laminae only partly overlap preceding laminae, and the preceding laminae having perforations under the overlapping laminae, and a coating substance permeating the interstices between the overlapping parts of the laminae and extending through said perforations, for a purpose as set forth.

10. The method of roofing which consists in laminating perforated roofing elements with the perforations of some of the elements interlaid by an unperforated part of another of the elements, together with a coating substance between the elements and extending through the perforations thereof.

11. The method of roofing which consists

in providing a longitudinally alined series of perforations in a roofing material at a required interval across said material, and laying some parts of said material to overlap other parts thereof with the edges of the overlapping parts barely overlapping the alined perforations of the overlapped parts.

12. The method of roofing which consists in providing a longitudinally alined series of perforations in a roofing material at a required interval across said material, and laying some parts of said material to overlap other parts thereof with the edges of the overlapping parts barely overlapping the alined perforations of the overlapped parts, and, in conjunction with the laying operation, applying a coating substance between the overlapping parts and in said perforations.

13. The method of roofing which consists in providing longitudinally alined series of perforations in a roofing material at required intervals across said material, cutting some parts of said material along a longitudi-

nally alined series of perforations thereof, and laying some parts of said material to overlap other parts thereof with the edges of the overlapping parts barely overlapping the alined perforations of the overlapped parts.

14. The method of roofing which consists in providing longitudinally alined series of perforations in a roofing material at required intervals across said material, cutting some parts of said material along a longitudinally alined series of perforations thereof, and laying some parts of said material to overlap other parts thereof with the edges of the overlapping parts barely overlapping the alined perforations of the overlapped parts, and, in conjunction with the laying operation, applying a coating substance between the overlapping parts and in said perforations.

OSCAR A. BIGLER.
